UNITED STATES PATENT OFFICE

2,425,517

HOBBYHORSE

Harry C. Dollar, Mebane, N. C.

Application October 16, 1944, Serial No. 558,889

2 Claims. (Cl. 272—52)

1

This invention relates to a toy and more particularly to such toy as a hobby horse or the like.

The primary object of this invention is the provision of an improved hobby horse which will provide increased amusement and entertainment for small children.

An additional object of this invention is the provision in a hobby horse, with means whereby the head of the horse will bob in a realistic manner when pulled upon by the reins associated therewith.

Still another object is the provision of such a toy provided with means whereby the head may be pulled downwardly in accordance with the desires of the operator, and returned to normal position, as by resilient means.

Still other objects reside in the combinations of elements, arrangement of parts, and, features of construction, all of which will be more fully pointed out hereinafter and disclosed in the accompanying drawings, wherein there is shown a preferred embodiment of this inventive concept.

In the drawings:

Figure 1 is a side elevational view of a hobby horse embodying features of this inventive concept.

Figure 2 is a top plan view of a fragmentary section of the horse's head.

Figure 3 is a bottom plan view of certain constructional details.

Figure 4 is an enlarged side view, partially in elevation, disclosing the head of the horse, certain portions thereof being removed.

Figure 5 is a sectional view taken substantially along the line 5—5 of Figure 1.

Like reference numerals refer to like parts throughout the several views of the drawing.

Having reference now to the drawings and more particularly to Figure 1 there is generally indicated at 10 a hobby horse body of conventional design provided with supports 11 terminating in rockers 12. As shown in Figure 4 however, the neck portion 13 of the horse terminates an arcuate surface member 14 provided with an abutment 15. The head portion of the horse is comprised of two side plates 16 and 17 respectively adapted to simulate a horse's head, and terminating in arcuate surfaces 18 extending downwardly about the neck portion 13 of the horse. Positioned between plates 16 and 17 is a relatively solid member 19 having an arcuate surface 20 with a radius of curvature substantially equal to that of arcuate surface 14.

It will be seen that a substantial space between side plates 16 and 17 exists between the front

2

edge of portion 13 and the arcuate surface 20 of portion 19. Positioned within this space is a coil spring 21, one end of which is secured to an eye 22 secured to the front of portion 13 and the other end of which is secured to an eye 23 secured adjacent the lower portion of arcuate surface 20 of member 19. The head assembly is mounted for pivotal movement on the neck portion 13 as on a pivot 25. Reins 26 are secured as by pins or rivets 27 to the opposite sides of side plates 16 and 17, and extend rearwardly to a position adjacent to the saddle 28 of the body 10.

Now from the foregoing it will be readily understood that the hobby horse is operated in a conventional manner, and a pull on the reins 26 will draw the head downwardly, through the coaction of arcuate surfaces 14 and 20 until such time as the lower edge of member 19 abuts the forward surface of member 13. It will likewise be seen that when the pressure on the reins 26 is released the spring 21 will bias the parts back to the position shown until the extreme rear edge of member 19 strikes the abutment 15 whereupon the parts will remain in the position shown in Figure 1.

Now from the foregoing it will be seen that there is herein provided a toy and amusement device accomplishing all the objects of this invention, and others including many advantages of great practical utility and material entertainment value.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a device of the character described in combination, a body, a neck portion having an arcuate extremity extending from said body, a head portion comprised of side plates and a central member, said central member having an arcuate concave surface of a radius of curvature equivalent to said first mentioned arcuate surface and coacting therewith, means pivotally mounting said head portion to said neck portion, means to move said head portion about said pivot, and resilient means between said head portion and neck to bias the head portion against the pressure of said last mentioned means.

2. In a device of the character described in combination, a body, a neck portion having an arcuate extremity extending from said body, a head portion comprised of side plates and a cen-

tral member, said central member having an arcuate concave surface of a radius of curvature equivalent to said first mentioned arcuate surface and coacting therewith, means pivotally mounting said head portion to said neck portion, means to move said head portion about said pivot, resilient means between said head portion and neck to bias the head portion against the pressure of said last mentioned means, and stop means precluding movement of said head portion beyond 10 predetermined points in either direction.

HARRY C. DOLLAR.
